UNITED STATES PATENT OFFICE.

AUGUSTUS STEIGER COOPER, OF SANTA BARBARA, CALIFORNIA.

WINNING AMMONIUM GAS.

Application filed January 18, 1922. Serial No. 530,058.

To all whom it may concern:

Be it known that I, AUGUSTUS S. COOPER, a citizen of the United States, residing at Santa Barbara, in the county of Santa Barbara and State of California, have invented certain new and useful Improvements in Winning Ammonium Gas, of which the following is a specification.

In various parts of the country throughout the West and particularly throughout the coast ranges of California there are scattered a number of solfataras where spontaneous combustion of the bitumen in the shales is in operation. This earth formation is particularly found in a bluff or steep declivity and on their surfaces, salts of ammonia have been found to be present. In parts of California, in particular, the shales in the bluffs of the ocean are undergoing spontaneous combustion. The voids in the shales composing the bluffs are filled or partly filled with porous, brown bitumen the same being composed of unsaturated hydrocarbon, with nitrogen and sulphur compound. From the vents in the bluffs sulphur and ammonia gases escape. The air supporting combustion enters the lower portion of the bluff and the spent gases escape in the upper part thereof and the formation of the ocean bed some distance from the shore consists of burned shales, showing that combustion has been going on for a long time.

In another section of California the bluff of the ocean was excavated for a road bed and the bluff graded to various angles. Fragments of the shales containing porous, brown bitumen were dumped over the bluff which formed conical piles on the sand bed of the beach. When the winter rains commenced, spontaneous combustion ensued. Many fragments of the shale were burnt to a brick red and some seemed to have been melted in their interior, which oozed out on their sides. Strong fumes of sulphur and the acrid odor of ammonia filled the air.

The primary object, therefore, of the invention is to obtain ammonia, carbonate of ammonia and other ammonium salts from the porous, brown bituminous shales present in the earth formation, above referred to. The brown, porous bitumen consists of the unsaturated carbons, sulphur and nitrogen compounds which when readily oxidized forms carbon dioxide, sulphur dioxide and

ammonia gases, the bitumen being exceedingly porous, and along the surfaces presented to the action of the oxygen of the atmosphere.

Reference being had to the drawing showing one form of the apparatus resorted to to obtain the products above referred to from the brown, bituminous shales, a compressor designated A is a resort to in forcing atmospheric air into the earth formation. The atmospheric air is heated by a suitable heater B, since the heated oxygen acts more energetically than when cold to accelerate combustion. The heat of the spent gases of combustion also heats the air that is being forced into the earth formation and in many cases, is sufficient without resorting to the use of the heater B. D and E designate pipes leading to the bottom of a bored well or hole F. The heated oxygen in the air is discharged into the well and of course, comes in contact with the brown bitumen, so that spontaneous combustion sets in and the carbon dioxide, sulphur dioxide and ammonia gases are formed. The burnt shales contract from 5% to 10%, leaving innumerable cracks for the entrance of the atmosphere and the action of the spent gases of combustion. The heated gases passing through the pipe C heat the atmosphere in the pipes D and E, it being found that the gases of combustion consist, primarily, of hydrogen sulphide, sulphur dioxide, carbon dioxide and ammonia gases. A tank H, filled with water, receives the gases above referred to and since the same are very soluble in water, a large amount goes into solution therewith. Through the inter-action of the ammonia gases, sulphur dioxide, carbon dioxide and oxygen, sulphate of ammonia and other ammonium salts are formed, from which the water may subsequently be removed by evaporation.

After the bitumen in the vicinity of the pipes D and E is distilled and burned up, the heated atmosphere is introduced into the shale through the pipes I, J. If the cracks through the shale do not connect the pipes I, J with the well or hole, the shale can be fractured by exploding black powder in the formation between the pipes I, J and the well above referred to.

The difficulty of getting a circulation of the atmosphere and spent gases through the shales is the only reason that numerous places are not undergoing spontaneous com-

bustion. There must be avenues for the entrance of the atmosphere in the lower portion of the shales and the exit of the gases in the upper part, otherwise the spent gases fill the interstices in the shales opposing the entrance of the atmosphere, then again the shales must be cracked and seamed to permit this circulation, so in accordance with my invention, as above referred to, this may be effected and by spontaneous combustion all the combustibles are removed from the shale. It will thus be seen that after a well or shaft has been dug that a great area of the shale may be acted upon to produce the combustion, so that the gases formed may be permitted to pass upwardly through the said well and treated to obtain the products above referred to.

Having described and shown my invention, what I now claim as new and desire to secure by Letters Patent of the United States is:

1. The process of obtaining ammonium salts from bituminous shales which consists in forcing heated, atmospheric air in the shales to increase the rapidity of spontaneous combustion, drawing off the gaseous products from the shales and dissolving the same in water and subsequently evaporating the water.

2. The process of obtaining ammonium salts from bituminous shales which consists in forcing heated, atmospheric air through an opening extending into the shales to in-

crease the rapidity of spontaneous combustion, introducing heated air into the shales in proximity to the opening to enlarge the area of combustion, drawing off the gaseous products from the shales and dissolving the same under water and subsequently evaporating the water.

3. The process of obtaining ammonium salts from bituminous shales which consists in forcing heated, atmospheric air through an opening extending into the shales to increase the rapidity of spontaneous combustion, introducing heated air into the shales in proximity to the opening, fracturing the shales about said opening to permit the passage of air, thus setting up increased combustion in the enlarged area about said opening, drawing off the gaseous products and dissolving the same under water and subsequently evaporating the water.

4. That step in the method of obtaining ammonium salts from bituminous shales, which consists in compressing air, heating the compressed air, forcing the heated compressed air in the shales to increase the rapidity of spontaneous combustion, and drawing off the gaseous products from the shales.

In testimony whereof I affix my signature in presence of two witnesses.

AUGUSTUS STEIGER COOPER.
